UNITED STATES PATENT OFFICE.

HARRY PHILLIPS, OF CHICAGO, ILLINOIS.

CHANDELIER.

SPECIFICATION forming part of Letters Patent No. 273,145, dated February 27, 1883.

Application filed May 12, 1882. (No model.)

To all whom it may concern:

Be it known that I, HARRY PHILLIPS, a subject of Great Britain, and a resident of Chicago, in the county of Cook and State of Illinois, have invented certain new and useful Improvements in Suspending Chandeliers, of which the following is a full, clear, concise, and exact description, reference being had to the accompanying drawings, in which—

10 Figure 1 is a side elevation of the device for regulating the height of chandeliers as embodied in my invention. Fig. 2 is a longitudinal central section thereof upon line $x-x$ of Fig. 1. Fig. 3 is a horizontal section upon line $y-y$ of Fig. 2, showing the distributor, with which the burners are connected, somewhat in detail. Fig. 4 is a detail elevation of one of the two grooved wedges or clamps which form the principal part of my automatic locking device.

Like parts are indicated by similar letters of reference in the different figures of the drawings.

The inner or first pipe, a , extends down 25 from the ceiling through the locking device, as shown, and all adjustments of the height of the chandelier are made by moving the locking device upon this pipe. The locking device consists of two grooved pieces or clamps, 30 $b-c$. These pieces are of the same shape, and are each provided with a spiral groove, d , as shown in Fig. 4. These clamps are placed about the pipe a , and when pressed together against the pipe there is sufficient friction between their inner concave surfaces and the 35 convex surface of the pipe to support any required weight. The second or central pipe, e , extends below the distributor, and is connected at the upper end with the clamps $b-c$ by means of the collars $f-g$. The cup h is connected with the outer or third pipe, i , as shown. The spiral spring k is placed under the collar f , and should be of sufficient force to support the weight of the central pipe, e , 45 and hold the clamps $b-c$ in engagement with the screws $l-m$, which are adjusted to the spiral grooves d in the said clamps. The central pipe, e , is provided with openings o , so that the gas may enter the distributor p . The 50 pipe e is plugged at the lower end, and pro-

vided with the burr or knob q . The pipe i may be provided with slots, as shown, so as to allow the knob q to move down a short distance, carrying with it the central tube or pipe, e . This independent downward motion 55 of the pipe e must be sufficient to loosen the locking device. The length of the slots in pipe i is otherwise immaterial. By pulling down on the knob q against the force of spring k , a downward spiral motion is imparted to 60 the clamps $b-c$. Thus, by simply pulling down on the knob q , the screws which project into the spiral grooves d are brought nearer to the upper and smaller portions of the clamps, so that the clamps are loosened sufficiently to allow them to slide upon the inner pipe or rod, 65 a . The pipe i is screwed into the distributor, as shown at p' and p'' , and the stuffing-box s prevents the gas from escaping between the pipes i and e . The stuffing-box r comes next 70 to the gas or stationary pipe a , and prevents the gas from escaping between said stationary pipe and the pipe e . The chandelier may thus be raised and lowered, as desired.

My locking device may be used with lamps 75 or candle-chandeliers. In this case I dispense with the packing $r-s$, and may use a rod instead of the pipe a .

My locking device works best when the clamps are grooved and used in combination 80 with the screws $l-m$. I find, however, that good results may be obtained by using clamps that are not provided with the spiral grooves, and dispensing entirely with the screws or projections $l-m$. This may be demonstrated 85 by simply removing the screws $l-m$ and using the device as hereinbefore described. When used without the screws $l-m$, the outer surfaces of the wedges come against the inner surface of the cup h , and thus sufficient friction is produced to hold the chandelier at any desired 90 height.

I claim—

1. The combination, substantially as hereinbefore set forth, of the spirally-grooved 95 wedges, with the adjustable projections, a spring for forcing the wedges against said projections, and means whereby a spiral motion may be imparted to the wedges, so as to bring the projections toward the smaller ends of the 100

wedges, thus removing the friction between the inner concave surfaces of the wedges and the opposing convex surface.

2. The locking device consisting of the clamps *b* *c*, each provided with a spiral groove, *d*, in combination with the screws or projections *l* *m*, the spring *k*, and pipe *e*, whereby a downward spiral motion may be imparted to the clamps on pipe *a*, substantially as and for the purpose specified.

3. The locking device consisting of the clamps or wedges, in combination with the cup *h*, the spring *k*, and pipe *e*, whereby sufficient friction may be produced to hold the chandelier, substantially as set forth.

HARRY PHILLIPS.
